MECHANISM FOR DECORTICATING FIBERS
OBTAINED FROM THE LEAVES OF SISAL
AND LIKE PLANTSJames McCrae, Longonot Estate, Naivasha,
Kenya Colony, East AfricaApplication July 26, 1937, Serial No. 155,683.
Renewed March 8, 1940. In Great Britain
August 6, 1936

3 Claims. (Cl. 19—15)

This invention relates to mechanism for decorticating fibers obtained from the leaves of sisal and other plants, and my present invention consists in devices and mechanism for further 5 treating the fibers after they have been prepared and acted upon by the mechanism described in the specification of my further concurrent application for Letters Patent Ser. No. 155,682, filed simultaneously herewith, or fibers similarly 10 treated by any other process than that as explained by my said specification.

My said invention comprises the employment of machinery or mechanism for carrying out the treatment whereby the force acting upon the 15 threads of fibers lays such stress or tensional strain thereon that the separate fibers in their natural bundled state are forced or burst asunder or caused to separate in increasing degree from each other (as well as all the other substances 20 accompanying same), the said process of separation being carried out to any desired degree appropriate to the preparation of the fibers for any of the particular purposes for which they may subsequently be used.

25 In carrying my invention into effect I make use of the mechanism and devices hereinafter described by reference to the accompanying sheets of drawings, in which:

Fig. 1 is a sectional end elevation showing the 30 operating belt devices for feeding the prepared leaves to two pairs of lattice belt devices carrying blades for subjecting said leaves to their penetrating, removing and cleaning operations on the fibers derived from said leaves.

35 Fig. 2 is a sectional plan of a portion of the devices shown by Fig. 1.

Fig. 3 is a similar view to Fig. 1 but shows one 40 pair of feeding belt devices in connection with one pair of lattice belt carrying blade devices, the same being drawn to an enlarged scale in order more clearly to illustrate the construction of my improved parts.

Fig. 4 shows the chain supporting wheel upon 45 which the belt-gripping-devices shown by Fig. 3 are mounted, said belt gripping devices being mounted upon the chains arranged according to my invention.

Fig. 5 is a side elevation of one of my improved 50 piercing, removing, smoothing and scraping blades mounted upon one of the lattice bars forming the lattice driving belt shown by Figs. 1, 2 and 3.

Fig. 6 is a side elevation of the members shown 55 by Fig. 5 as seen looking from right to left of said figure.

Fig. 7 shows a modification of the blade and the method of mounting same as compared with Fig. 5.

Fig. 8 also shows a modification of said blade and the method of mounting same upon the 5 lattice bar.

Fig. 9 is a drawing in detail showing a method of securing the blade carrying member mounted upon the lattice bar referred to.

Fig. 10 shows a modification in the shape of 10 the operating blades shown by Figs. 5, 6, 7 and 8, said modification comprising the said formation to enable said blade to act as is hereinafter fully explained.

Fig. 11 is a plan showing how the threads, as 15 they are separated and treated by the blades, are caused to be cleaned, strained and stressed as desired.

Fig. 12 is a plan drawn to a reduced scale 20 showing somewhat how the series of blades may be varied throughout the length of each of the lattice bars upon which said blades are mounted.

Fig. 13 is a diagrammatical plan and Fig. 14 a diagrammatical elevation (seen in the direction of arrow 40, Fig. 13) of the main operating parts of 25 a machine (drawn to a reduced scale) to show the relative positions of the said operating parts.

To attain the object of my invention I make use of feed mechanism comprising two pairs of 30 travelling chains 2, 2a and 2b, 2c, one chain of each pair 2 or 2b being superposed to travel in a path over the path in which the other chain of the pair 2a or 2c travels in order that the crushed leaves w (Fig. 3), with their cuticles or coverings and other matter, may be fed to the chains 3, 35 3a and 3b, 3c, as is hereinafter explained.

The formation and construction of said 40 travelling chains 2, 2a and 2b, 2c are such that their surfaces x (see Fig. 3) will contact with each other, and by being covered with india rubber 40 each chain carrying its respective rubber covering formed as shown at x (Fig. 3) is enabled to act as a jaw or gripping member that will firmly grip the sheets or bundles of fibers fed to them, the gripping actions being secured by 45 spring actuated members that force one chain against the other, while where necessary anti-friction bowls s may be mounted upon the chains to travel over the guiding rails 4 which support 50 them.

The india rubber belt surfaces x are endless so 55 that they may take over and circulate by the rotary actions of their operating sprocket wheels 5 which are mounted at the extremities of the 55

paths through which the belts 2, 2a, 2b and 2c travel.

Adjacent the vertical planes in which the gripping chains, 2, 2a, 2b and 2c operate, and 5 parallel therewith, are mounted two shafts 10, 10a and 10b, 10c respectively, by which arrangement the sprocket wheels mounted upon the shafts 10, 10a and 10b, 10c revolve in planes at right angles to the planes in which the gripper 10 chains 2, 2a and 2b, 2c travel.

Upon these shafts 10 to 10c are mounted the desired number of sprocket wheels (all of which are referred to as 11) so that the lattice belts or chains 3, 3a and 3b, 3c may take over these 15 sprocket wheels 11 and extend to take also over sprocket wheels 12 mounted upon shafts parallel thereto. These lattice belts 3 to 3c are provided with cross bars or staves 14, 14a and 14b, 14c, those staves at 14 and 14b being thus caused to 20 travel through paths vertically above the paths in which the staves 14a and 14c operate.

In appropriate base members 15 which are fixed upon the staves 14a and 14c are mounted blades 16 which have base parts 16a of appropriate construction or formation to suit their fitting within the hollow retaining member 15, from which it will be observed that the modification in said base part 16a, from fitting one fixing member or another fixing member, varies from 30 to the rectangular shape shown by Fig. 5 to those shown by Figs. 7 and 8, in each case the base member 15 being secured against rotation upon the stave or bar 14a by the fixing member 15w as circumstances necessitate.

35 Upon the staves 14 and 14b which travel in paths above the paths in which the staves 14a and 14c travel cross bars of an appropriate shape as shown by Fig. 3 have projecting strips 14w extending their length crosswise to overhang the spaces between the laths beneath.

40 The strips 14w which intervene between the base members 15 which carry the blades 16 as shown by Fig. 3, by pressing upon the leaves or fibers *t* extending from said leaves *w* will force those down between the blades 16 in order that 45 said blades may pierce the fibers *t*, or the fibers which have been extracted from said leaf while the said leaf is being still carried forward in the direction indicated by the arrows *v* shown in the several drawings.

50 The lattices 14, 14a, 14b and 14c are carried around their sprocket wheels 11 and 12 in order to be moved in the directions shown by the arrows *t²*. Thus it will be observed that the lattices described move in paths which are at right angles to the paths in which the feeding belts 2, 2a and 2b, 2c travel. Therefore as the belts 2, 55 2a, 2b and 2c are the feeding belts which receive the leaves *w* as they are fed thereto, these leaves 60 are carried laterally towards the ends or edges of the lattices referred to. By these means and since the leaves are fed at the feeding end of the chains 2, 2a, 2b and 2c (as shown by Fig. 4) they travel with the leading edges along the 65 paths of the chains described so that they encounter the projections 16 which are moving crosswise their path. Consequently these projections are caused to pierce the said leaves *w* and after piercing said leaves they move longitudinally along said leaf until all the loose matter 70 thereon and all the loose matter adhering, to the fibers from said leaves is carried away by the scraping actions of said members 16, and this engaging, removing and scraping (as well 75 as the separating actions that the blades 16

have upon the bundles of fibers *t* as these are passing over same) effects the complete separation of each fiber from its neighbour so that when finished at the end of their operations by the actions of the lattices 14 and 14a the 5 fibers from the leading end of the leaves are perfectly cleared and cleaned, while those from the rear edges are also cleaned and cleared in order to be deposited at the end of the path of motion of the chains 2b and 2c of the stationary 10 table or support from which they may be removed for packing, bundling or like treatment as may be desired.

In order to secure the desired scraping effect of the blades 16 upon the fibers *t* as they are 15 traveling through the machine, said blades are made with a curved front edge, a rounded top and a straight back edge as clearly shown in side views in Figures 5, 7 and 8, and in their simplest form are perfectly straight and even. 20 As previously stated the actual front edge corresponding to the thickness of the metal is square to the sides of the blade. The scraping effect may be increased if the top of the blade is offset as shown in Figure 10, while the upper end may 25 also be twisted to facilitate entry between the fibers. In this case the lower part of the blade is maintained square so that the angularity of these edges is an acute angle to the fibers *t* that are pulled against the rear edges 16w of the 30 blades 16 and said fibers will therefore be greatly stressed and made to spread so that on being next laid hold of by the succeeding blades the separate fibers will be engaged with on the opposite side of the next blade because of the separation and spreading actions referred to. Consequently such spreading actions are of importance in the quick working of the machine to perform the functions of scraping and cleaning as desired.

I may also have the blades 16 formed with 35 offset tips as shown at 16x (Fig. 10) in which case as the fibers come in contact with the inclined center parts they are strained downwardly and continue to move laterally during all the motions of the blades as carried by their respective lattices 14a and 14c. In this manner the dividing and splitting up of the bundles of fibers is effected so that ultimately each fiber 45 is separated from its neighbour and all the fibers are delivered in their separate positions and free 50 of each other, as well as being free of any gummy matter which in in nature is associated with them.

It may be found advantageous to have certain 55 of the upper ends 16y of the blades 16 twisted or turned from being in strict alignment with the path of motion of said blades as is shown by a blade at the end of the series shown by Fig. 11, since by being in that position they more readily will enter between the series of threads when such threads are at an angle to the line 60 of travel of the blades 16 as carried by their respective lattices.

These blades 16 are held in their base members 15 by the bases of said blades 16 fitting the longitudinal opening through their respective base holding members 15, and these may be of varied shapes as shown by Figs. 5, 7 and 8, where they are respectively rectangular in cross section, circular in cross section and semi-circular 70 in cross section.

The fixings at 15w are made to suit the outer contour of the openings made through them and of the bases of the blades 16 so that said base holding members 15 will be of the shapes or contour shown by Figs. 5, 7 and 8.

When the base members 15 are of cylindrical contour or semi-cylindrical contour, as shown by Figs. 7 and 8 the retaining or holding members 15w have an inwardly extending projection 30 shown by Fig. 9 so that said projection will fit in a slot extending lengthwise the cylindrical or semi-cylindrical retaining members 15 as shown by Figs. 7 and 8. Thus these latter are more firmly secured and held against rotation.

In order to secure the spaces between the blades 16 I have spacing pieces 31 of the proper contour that are placed within the retaining members 15 and 15w so that according to the number of said spacing pieces so will the distance or space apart be secured for the blades 16.

The spacing members, as well as the blades 16, are held together either by a rectangular bolt or bar 15s (shown by Fig. 5) extending through same and having its outer ends screw-threaded and nuts mounted thereon, or the cylindrical rods 15t may be used as is shown by Figs. 7 and 8, in which latter case the said rod has screwed nuts 15p mounted thereon to bind the whole together throughout the length of the member 15 within which they are mounted.

I may arrange said blades 16 to be spaced so that one section, as the commencing section shown on the left of the diagram (Fig. 12), may be the coarsest pitch, while the next may be of less pitch, and the succeeding ones again of lesser pitch in order that the threads passing through and between them to be cleaned and scraped by them will finally pass through the closer spaced blades at the right hand of Fig. 12, in which the scraping actions as described in reference to the stressing and angular strain put upon them and shown by Fig. 11 will be the final finishing of the threads before same are discharged from the machine.

In the treatment of the leaves as above described a tube or conduit 4x is made use of for conveying water (which may be hot or cold) through said tube 4x and along same to be supplied in jets through the orifices 4s leading from said jets, and which orifices may be covered by a plate 4f as is shown by Fig. 3 so that they may be shut-off or opened as occasion may require. It may be advantageous to have the conduit 4x in sections as it extends lengthwise the machines in order that the water or liquid supplied thereby may be varied for different sections in order that the last section when desired may supply a liquid containing soapy or

other ingredients to treat the fibers as they are passing between the finishing blades 16 shown at the extreme end of Fig. 12 of the drawings.

Figs. 13 and 14 diagrammatically show the passage of the leaves through the machine. First 5 they are fed to the feeding belts x, x. These carry them forward to encounter the lattice belts 14b which comb out the woody pulp and other matters from the fibers and continue so to do until these fibers leave the lattices 14b 10 and are carried by the belts x to the lattices 14 in order that after the former treatment of the fibers by the lattices 14b to clear the fibers in the extending ends of the leaves, the other lattices 14 clear the fibers from the root ends 15 of the leaves, thus depositing the finally finished fibers t³ cleaned throughout their whole lengths.

Such being the nature and object of my said invention, what I claim is:

1. In apparatus for treating fibers derived 20 from the leaves of sisal and like plants, feeding belts for carrying prepared leaves, two sets of travelling lattices mounted to travel laterally in two directions therefrom, tubular holders mounted on said lattices and extending transversely 25 thereon, each said holder having a longitudinal slot therein, a series of blades supported by each said holder, each said blade having a base portion within the holder, spacing elements within the holders between successive blades, and a longitudinal securing member extending through 30 each series of blades and the spacers associated therewith.

2. In apparatus for treating fibers derived 35 from the leaves of sisal and like plants, a set of travelling lattices, feeding belts adjacent to said lattices for carrying prepared leaves past said lattices, and series of blades on said lattices, some of said blades being twisted so that their free ends make acute angles with the direction 40 of motion thereof.

3. In apparatus for treating fibers derived 45 from the leaves of sisal and like plants, a set of travelling lattices, feeding belts adjacent to said lattices for carrying prepared leaves past said lattices, series of blades extending across said lattices, and spacers between successive blades in each said series, said spacers being progressively narrower from one side of the lattices to the other, some of said blades being 50 twisted so that their free ends make acute angles with the direction of motion of the blades.

JAMES McCRAE.
